UNITED STATES PATENT OFFICE

HERMAN B. KIPPER, OF MUSKEGON, MICHIGAN

HEATING AND AGITATING APPARATUS

Application filed March 3, 1924. Serial No. 696,485.

This invention relates to an apparatus which is designed for the carrying out of certain processes, one of which may be the recovery of the by-products from coal; another, the recovery and distillation of petroleum products from shale rock. And the apparatus is designed to be used wherever the application of heat to the material acted upon by the heat and accompanied by a simultaneous stirring of the material together with a continual grinding or pulverizing of the material during the time that the heat is applied is desirable.

It is the primary object and purpose of this invention to produce an apparatus by means of which the process above outlined may be very economically carried out. A further object of the invention is to produce an apparatus which is capable of withstanding the severe usage to which it is put during service and one particularly capable of withstanding the high temperatures which are used with the same, as well as any other objects and purposes not at this time specifically stated but which will appear fully and in detail as understanding of the invention is had from the accompanying drawing in which,

Fig. 1 is a longitudinal vertical section of the apparatus of my invention.

Fig. 2 is an end elevation of the same looking at the structure shown in Fig. 1 from the left, and

Fig. 3 is a transverse vertical section through the construction shown in Fig. 1.

Like reference characters refer to like parts in the different figures of the drawings.

In the construction a cylindrical drum 1 of suitable metal is used open at both ends and covered with heat insulating material 2 which may be brick or equivalent material. Against the ends of the cylinder 1 circular heads 3 may be placed which completely close the open ends of the drum. A hollow shaft 4 passes through the heads 3 and is supported by suitable bearings at the upper ends of posts 5 located at each end of drum. A pulley 6 is fastened to shaft 4 and is adapted to be driven by a belt 7 from any suitable source of power. Water is supplied by a pipe 8 to one end of the

hollow shaft 4, the amount thereof being controlled by manually operated valve 9 in pipe 8, the water passing through the pipe and through shaft 4 and being carried away through any suitable waste pipe 10 at the opposite end of the shaft 4.

A plurality of bars 11, in the present apparatus shown as four in number, though this number may be changed, extend lengthwise through the cylinder 1 closely adjacent the inner walls thereof and pass through openings in the head plates 3. The bars are placed around and are connected to metal rings 12 which are located in spaced apart relation within the drum 1. Coiled springs 13 are mounted upon the outer ends of the bars 11 and are held between the outer sides of the head plates 3 and pins 14 which pass through the bars 11. These springs under compression serve to press the head plates 3 against the ends of the drum 1. It will be noted that the bars 11 are formed with one edge brought to substantially knife point and with the movement in the direction indicated by the arrow in Fig. 3, said bars serve as scrapers to keep any of the material introduced into the cylinder 1 from baking against or otherwise becoming secured to the inner walls of the drum, the movement of the bars causing a continual stirring of the material within member 1. The head plates 3 are provided with gear teeth 15 around the same. Two shafts 16 and 16^a pass through the covering material 2 to which pinions 17 and 17^a are fixed, these pinions being in mesh with the teeth 15. The location of the shafts and pinions is best shown in Fig. 2, the end plates 3 bearing thereon. Said shafts 16 and 16^a are supported adjacent their ends by suitable posts 18.

A small pulley 19 is fixed on the hollow shaft 4 around which a belt 20 passes, the belt also passing around a pulley 21 which is attached to one end of a short shaft 22 and which, through an intermediate gear reduction in the housing 23, drives another shaft 24 at reduced speed. The shaft 24 is connected to and alines with the shaft 16. It is evident from this construction that the head plates 3 are rotated slowly in comparison to

the speed of rotation of the hollow shaft 4 whenever the apparatus is in use, and such rotation of the plates 3 serves to move the scraping bars 11 at a comparatively slow 5 rate of speed.

The hollow shaft 4 is covered the greater portion of its length within the drum by suitable protective material 25 which may be placed within outer sleeves 26. At spaced 10 apart distances on the shaft 4, plates 27 are located between the ends of the sleeves 26, each having radially extending arms through which rods 28 pass. Beater bars 29 are mounted on the rods 28 by means of short 15 links 30 which are pivotally connected to the rods 28. A plate 72°, as shown in Fig. 1, may be mounted eccentrically on the shaft 4 and bars, somewhat curved attached thereto at one end by means of small brackets 31 20 and at the other end to the adjacent plate 27. The construction may be used to aid in feeding the material from the point where it is entered into the apparatus toward the discharge end thereof.

25 The material to be treated may be passed into the drum 1 through an inlet pipe 32 adjacent which is a second pipe 33 for the introduction of heated air or other source of heat. It will be noted the opening in the 30 drum at the lower end of pipe 32 is flared downwardly, this insuring that material will not clog or stick on its way to the said member. Also the beating and feeding apparatus mounted on the shaft 4 is not extended 35 underneath the pipe 33 so that material is not thrown up into said pipe to clog the same.

40 Adjacent the opposite end of the apparatus, a discharge pipe 34 is provided at the lower side of the drum and a second discharge pipe 35 at the upper side of said drum in which a damper 36 or other control is mounted. The discharge pipe 34 leads to a chamber 37 from which an outlet pipe 38 45 leads adjacent the upper portion of said chamber; and an inclined pipe 39 is mounted in the chamber with its lower end near the lower side of said chamber in which a suitable screw conveyer 40 is mounted.

50 In operation, the material to be acted upon being introduced through the pipe 32 is acted upon by heat supplied through the pipe 33. At the same time the shaft 4 is rotated and the bars 29 strike and beat the material to 55 maintain it in pulverized state, while the bars 11 continually scrape the same from the inner walls of member 1 and stir it in addition to the continual agitation of said material by the beater bars 29 and the curved extensions located at the left hand portion of the apparatus. This continual agitation and beating of the material with the application of heat causes a very rapid action of the heat thereon. The material before entrance 60 65 may be broken up and ground and the agita-

tion and beating of the same while in the apparatus insures that it will remain in a finely divided or pulverized state, thereby giving the heat access to the particles for action thereon. A large quantity of the material can be treated in this manner where a much smaller quantity only could be successfully treated otherwise. 70

The products resulting pass through the discharge opening into the chamber 37; or in some instances part of the products pass out through the pipe 35. For instance, in the treatment of coal to secure the gaseous products thereof and coke all of the products are passed to the chamber 37, the gases being drawn out through the pipe 38 to any desired place where the same may be condensed in combination with the usual methods employed in scrubbing the by-product gas for light oil and ammonia. The solid products are conveyed from the chamber 37 through the agency of the conveyer 40 in the outlet pipe 39. Ordinarily the chamber 37 is merely insulated to prevent the escape of heat, but of course, if necessary it would be heated to 90 keep any desired temperature. In the treatment of shale rock for the recovery of petroleum products the more volatile gases escape through the pipe 35, while the rock passes to the chamber 37 together with heavier gases 95 coming from the distillation.

This apparatus is practical in every respect and has so proved in service. The passage of water through the shaft 4 together with insulation of the shaft by the material 25 serve to keep down the temperatures of the shaft whereby bearing troubles in the head plates 3 and in the bearings at the upper ends of posts 5 are avoided. The beater bars 29 are shaped so as to give the greatest efficiency though it is to be understood that the particular and specific shape may be varied without departing from the invention. Many other details of the structure and parts thereof may be modified in various ways without departing from the invention and I accordingly do not wish to be limited other than as defined by the appended claims covering the invention. The specific disclosures made, while of a practical and operative device is to be considered rather as diagrammatic of the invention and not as limiting the same to any specific constructive details. 100 105 110 115

I claim:

1. An apparatus of the class described, comprising a cylindrical drum open at both ends adapted to receive material to be treated, a head plate at each end of the drum for closing the same, bars disposed between the said plates and connected with the same to turn therewith, said bars lying in close adjacency to the inner walls of the drum, means for rotating the said plates at comparatively slow speed, a shaft extending lengthwise of the 120 125 130

drum and through said plates, means for driving said shaft at comparatively high speed, means for applying heat to material in said drum and bars movably mounted on the shaft for beating and grinding material located within the drum, substantially as described.

2. An apparatus of the class described, comprising a hollow container adapted to receive material to be treated, means for heating the material to a very high degree of temperature, rapidly moving means for maintaining the material in a broken or pulverized state and for moving it lengthwise of said container, slow moving means for scraping the material free from the inner walls of the container, and means for conducting the products of treatment of the material from the container.

3. An apparatus of the class described, comprising a hollow container adapted to receive material to be treated, means for heating the material to a high degree of temperature, means operated at a high rate of speed for continuously pulverizing the material and simultaneously moving it lengthwise of the container, and means operate at a much slower rate of speed for continuously scraping the material free from the inner walls of the container.

4. An apparatus of the class described, comprising a cylindrical drum having open ends, a head plate closing each end of the drum, bars carried by and between the plates closely adjacent the inner walls of the drum, means for turning said plates in unison, means for introducing material into the drum, means for heating said material, means for the discharge of the material from the drum after treatment thereof, and means for maintaining said material in pulverized state in the drum.

5. An apparatus of the class described, comprising a cylindrical drum having open ends and adapted to hold material to be treated, a head plate closing each end of the drum, means for heating material in the drum, a shaft passing through the plates, pivotally connected beater bars mounted on the shaft and lying lengthwise of the drum, means for driving the shaft, means for rotating said plates at a slower speed than said shaft and means carried by said heads for scraping the inner walls of the drum, substantially as and for the purposes described.

6. An apparatus of the class described, comprising a cylindrical drum having open ends, a head plate closing each end of the drum, means for heating material held in said drum, bars located closely adjacent the inner walls of the drum between the heads and extending through said heads, a spring on the outer end of each bar and a pin passing through the end of each bar, the springs being located between the pins and outer sides

of the heads, means for introducing material to be treated into the drum at one end thereof, means for effecting the discharge of said material and its products after treatment from the opposite end of the drum, and means for continuously beating and grinding the material within said drum during its treatment, substantially as described.

7. An apparatus of the class described, comprising a hollow member having opposed open ends, a plate closing each end of the member, means for holding the plates in tight engagement with said member, means connected with said plates for movement therewith to scrape the inner walls of the member, means for supplying material to said member near one end thereof, means for effecting the discharge of the products of treatment of said material adjacent the opposite end of the member, means for supplying heat to the material, and means for maintaining the material in pulverized state while in the said member.

8. An apparatus of the class described, comprising a cylindrical drum adapted to hold material to be treated, means for heating said material in the drum, a shaft located centrally of and extending through the drum, plates located in spaced apart relation on the shaft, rods extending through the plates at a distance from the shaft, said rods being spaced apart around the shaft, beater bars pivotally mounted on the rods, means for driving the shaft at relatively high speed, and means for continuously scraping the inner walls of the drum during the time the shaft is rotating.

9. An apparatus of the class described, comprising a cylindrical drum having open ends, a plate closing each end of the drum, means for applying heat to material held in said drum, a shaft passing through the plates and lengthwise of the drum on which said plates are rotatably mounted, bearings for the shaft, means for driving the shaft, other plates secured to the shaft in spaced apart relation, rods carried by said other plates at a distance from the shaft, links pivotally mounted on the rods, bars carried by the links substantially parallel to said rods, scraper bars located between and carried by said first plates and mounted closely adjacent the inner walls of the drum, and means for turning said first plates at relatively low speed, substantially as described.

10. A construction containing the elements in combination defined in claim 9, combined with means for driving said first plates from said shaft, means for introducing material into the drum adjacent one end thereof, means for effecting the discharge of the products of the material adjacent the opposite end of the drum, and means for cooling said shaft, substantially as described.

11. An apparatus of the class described,

comprising a cylindrical drum having open ends and provided adjacent one end with an inlet conduit for the passage of material to be treated into the drum and a second inlet conduit for the supplying of a heat there-
5 through, and further provided adjacent its opposite end with a discharge outlet, plates closing the open ends of the drum, said plates having gear teeth cut around the same, two shafts mounted parallel to the longitudinal
10 axis of the drum, two pinions on each shaft on which the said plates ride, means for driving one of the shafts at comparatively low speed, scraper bars carried by and between the plates close to the inner walls of the drum,
15 and means continuously operable while the plates are turning for beating and pulverizing the material within the drum.

12. An apparatus of the class described, comprising a cylindrical drum having open
20 ends and adapted to receive material to be treated by application of heat thereto, means for heating the material within the drum, means for closing the ends of the drum comprising end plates, means for driving said
25 plates to rotate them in unison, scraper bars carried by and between the end plates close to the inner walls of the drum, a shaft extending centrally of the drum and through the plates, heat insulating material over the
30 shaft, members connected to the shaft in spaced apart relation, rods carried by the members, beater bars paralleling the shaft pivotally connected to said rods, and means for driving the shaft simultaneously with the
35 rotation of said end plates but at a higher rate of speed.

13. An apparatus of the class described comprising a cylindrical drum adapted to hold material to be treated, means for heating the material in the drum, a shaft located centrally of and extending through the drum, said shaft having a longitudinal central passage therethrough, means for circulating a
40 cooling fluid through said shaft, the insulation means covering said shaft, means for rotating the shaft at high speed, beating and grinding members mounted on the shaft at a distance therefrom to act upon the material within the drum, means for scraping material from the walls of the
45 drum and means for driving said means at a much slower speed than the speed of movement of the beating and grinding means connected to said shaft substantially as described.

In testimony whereof I affix my signature.
HERMAN B. KIPPER.
